2 SHEETS—SHEET 2.

By M. Randolph, Atty.

UNITED STATES PATENT OFFICE.

LEWIS L. MILLARD, OF NORDEN, NEBRASKA.

SNOWPLOW.

1,359,090.

Specification of Letters Patent. Patented Nov. 16, 1920.

Application filed October 7, 1919. Serial No. 329,159.

To all whom it may concern:

Be it known that I, LEWIS L. MILLARD, a citizen of the United States, residing at Norden, in the county of Keyapaha and 5 State of Nebraska, have invented certain new and useful Improvements in Snowplows; and I do hereby declare the following to be a full, clear, and exact description of the invention, such as will enable others 10 skilled in the art to which it appertains to make and use the same.

This invention relates to new and useful improvements in snow plows and has for one of its objects the provision of a device of 15 this character which can be easily and conveniently applied to an automobile, truck, or motor vehicle so that roadways can be quickly cleared of snow of considerable depth and which devices can be easily removed when desired and will not interfere 20 with the cranking or starting of the automobile or truck when applied thereto.

Another object of this invention is the provision of an inclined mold board supported in spaced relation to the ground at its 25 forward end by runners which are adapted to act as knives in cutting the snow into strips as the snow engages the mold board so as to prevent the snow from banking or 30 packing against the mold board, thus requiring less power to shove the device forward.

A further object of this invention is the provision of a snow plow of the above stated 35 character, which shall be simple, durable and efficient, and which may be manufactured and sold at a comparatively low cost.

With these and other objects in view as will become more apparent as the description 40 proceeds, the invention consists in certain novel features of construction, combination and arrangement of parts as will be hereinafter more fully described and claimed.

45 For a complete understanding of my invention, reference is to be had to the following description, and accompanying drawings, in which:—

Figure 1 is a side elevation of a snow plow 50 constructed in accordance with my invention and illustrating it attached to a motor vehicle,

Fig. 2 is a front elevation of the same,

Fig. 3 is a transverse sectional view illustrating the shape of the mold board,

Fig. 4 is a longitudinal sectional view illustrating the means of securing the snow plow to the motor vehicle,

Fig. 5 is a bottom plan view of the device.

Referring in detail to the drawings, the 60 numeral 1 indicates as an entirety a snow plow consisting of a mold board 2, the forward edge of which is disposed straight to form a cutting edge 3. The mold board 2 is provided with an offset portion 4 that is of 65 substantially V-shape in cross section and diverges from its forward end in the direction of its rear end to form inclined faces 5 bordered by marginal flanges 6 so that snow engaged by the cutting edge 3 is deflected laterally in each direction by the inclined faces 5 and set off of the mold board to each side of the roadway by the marginal flanges 6. The rear edge of the offset portion 4 of the mold board slightly curves as illustrated at 70 75 7 to aid in deflecting the snow laterally in each direction.

A plurality of relatively spaced runners 8 are secured to the bottom face of the mold board 2 and extend forwardly of the cutting edge 3 and have their forward ends curved upwardly in arcuate shape to form cutting knives 9 that are connected together by a rod 10 on which is positioned spacing collars 11 so as to hold the knives in their proper relation. The intermediate runner is disposed within the offset portion 4 of the mold board 2 so as to strengthen and reinforce the same.

A pair of supporting rods 14 and 15 are 90 secured to the under face of the mold board 2 and extend beyond the rear edge thereof and are connected together by a brace 16. The supporting rod 14 has one end disposed at right angles to form an attaching or 95 journaling arm 17 that is disposed within one end of the sleeve 18. The sleeve 18 is secured to the forward end of a power driven vehicle 20 by suitable clamps 21. The supporting member 15 is of a shorter length 100 than the member 14 and has pivoted thereto an arm 22 which has a right angled end adapted to be disposed within the other end of the sleeve 18 whereby the supporting members are pivotally connected to the power driven vehicle. The arm 22 is provided with a handle 24 that overlies the arm 15 and is held in alinement therewith by a fastening element 25. The fastening element 25 may be slid off of the member 105 110

15 so as to permit the arm 22 to be swung on its pivot for disengaging the right angled end thereof from the sleeve 18 when desiring to disconnect the device from the vehicle.

- From the foregoing description taken in connection with the accompanying drawings, it will be noted that the plow is supported in an inclined position forwardly of the 10 motor driven vehicle so that on the plow being shoved forwardly by the vehicle, the snow will be cut into strips by the knives and passed onto the mold board 2 whence it is deflected laterally in each direction of 15 the roadway. The rear end of the mold board terminates substantially in a plane with the upper end of the radiator of the motor vehicle so as to permit the device to be used in comparatively deep snow. It will 20 also be noted that the cutting edge 3 of the mold board is supported in spaced relation to the ground so that stones and other obstructions may pass under the cutting edge without affecting the device.
- 25 While I have shown and described the preferred embodiment of my invention, it will be understood that minor changes in construction, combination, and arrangement of parts may be made without departing 30 from the spirit and scope of the invention as claimed.

Having thus described my invention, what I claim is:—

- 35 1. A snow plow comprising a mold board, supporting members secured to the mold board, a right angled extension formed upon the end of one of the supporting members, an arm pivoted to the other supporting

member and having a right angled end, a sleeve receiving the right angled ends and secured to a motor vehicle, means holding the arm against pivotal movement on one of said supporting members, and means supporting the mold board at its forward edge in spaced relation to the ground and adapted to cut snow into strips. 40 45

2. A snow plow comprising a body having its forward edge disposed straight to form a cutting edge, said body being curved to form an offset portion of substantially V-shape in cross section and having marginal deflecting flanges at its side edges, said V-shaped offset portion diverging from the cutting edge in the direction of the rear edge of said body, means securing the body to a vehicle, and 50 55 runners secured to said body.

3. A snow plow comprising a body having its forward edge disposed straight to form a cutting edge, said body being curved to form an offset portion of substantially V-shape in cross section and having marginal deflecting flanges at its side edges, said V-shaped offset portion diverging from the cutting edge in the direction of the rear edge of said body, means securing the body to a vehicle and spaced strips secured to the 60 65 offset portion and projecting forwardly of the cutting edge and curved upwardly to form combined knives and runners to said body. 70

In testimony whereof I affix my signature in presence of two witnesses.

LEWIS L. MILLARD.
